Primary Examiner — Rebecca Tsehay(74) *Attorney, Agent, or Firm* — Oblon, McClelland,
Maier & Neustadt, L.L.P.**CLAIM**

The ornamental design for a case for smokers' accessory, as shown and described.

DESCRIPTION

FIG. 1 is a front and left side perspective view of a case for smokers' accessory showing the new design.

FIG. 2 is a rear, top, and right side perspective view thereof.

FIG. 3 is a front elevational view thereof.

FIG. 4 is a rear elevational view thereof.

FIG. 5 is a top plan view thereof.

FIG. 6 is a bottom plan view thereof.

FIG. 7 is a left side elevational view thereof.

FIG. 8 is a right side elevational view thereof; and,

FIG. 9 is an enlarged view of callout circle 9 in FIG. 1.

The broken lines consisting of short and long dash lines encircling the enlarged detail views are for annotative purpose that form no part of the claimed design.
